DISPOSABLE SYRINGE

Robert W. Ogle, Pasadena, Calif.

Application November 17, 1950, Serial No. 196,198

3 Claims. (Cl. 128—218)

1

This invention relates to surgical syringes and more particularly to a type of syringe which is designed to be manufactured at a very nominal cost thus enabling the device to be used but once and then discarded.

It is one of the objects of this invention to provide a syringe which can be formed with its major parts molded from a plastic such as polyethelene thus reducing the cost of the finished article to a point where it is economically feasible to sell a syringe filled with a single dose or injection thus permitting the device to be discarded after a single use.

It is a further object of this invention to provide a unitary structure consisting of a syringe body, syringe plunger, needle, cork and vial, which when assembled and filled, is in the condition to be furnished to the medical profession and it is a feature of this assembly that as so assembled and sold the fluid will be displaced initially upon one side of the body and the plunger upon the other.

It is another object of this invention to provide such an assembly which in the condition furnished to the medical profession has the needle entirely protected and sealed against contamination and it is a feature of this assembly that a long hollow cork is provided for the vial which serves not only to close the vial prior to use but to seal off the needle thus protecting the needle against destruction and also contamination.

It is another object of this invention to provide a syringe of the type described which can be aspirated and in which the plunger can be manipulated prior to use, first to fill the body of the syringe with the injectable fluid, and second to remove all air bubbles.

It is a further object of this invention to provide a syringe of the type described in combination with a vial for the purpose of providing a prepared package containing in the body of the syringe a powdered medicament and in the vial a diluent for the powder, each of which is sealed against contamination or intermixture, but in which means is provided for opening communication between the syringe body and vial, when ready for use, for thorough mixture of the diluent and the powdered medicament.

It is a further object of this invention to provide a syringe and vial as set forth in the preceding paragraph in which the vial and syringe body remain sealed after such communication is established to prevent contamination and yet permit working of the diluent back and forth

2

from vial to syringe body for thorough mixing. These and other objects, features and advantages of the present invention will be apparent from the annexed specification in which:

Figure 1 is a vertical section of a syringe embodying the present invention shown in its initial or assembled position.

Figure 2 is a view similar to Figure 1 of the syringe shown in its position just prior to filling the body of the syringe with the injectable fluid.

Figure 3 is a side view of the device shown in the position occupied when the fluid is drawn into the body.

Figure 4 is an enlarged fragmentary vertical section of the lower end of the device in position similar to that shown in Figure 3.

Figure 5 is a fragmentary section showing an alternative embodiment of the lower end of the plunger.

Figure 6 is a section on line 6—6 of Figure 1.

Figure 7 is an exploded view of the parts in elevation.

Referring now more particularly to the drawings, the syringe is shown as comprising a body member 10, a plunger 11, a vial 12 and a hollow cork or plug 13. The body 10 is cylindrical in form and is provided with a flange 14 at its upper end and a tapered bottom 15. A hollow needle 16 is centrally disposed in the lower end of the body 10 which is conventional in form and provided with a tapered opening 17. The upper end of the needle 16 terminates at the lowest point of the tapered bottom 15 as clearly shown in the figures.

The body 10 has a reduced portion 19 forming a hub and from the shoulder thus formed one or more pins 20 depend. The reduced portion 19 adjacent the shoulder is slightly enlarged, shown as exaggerated at 19a for a purpose hereinafter described.

The plunger 11 is cylindrical in form and so dimensioned as to have a small clearance with the interior of the body 10. The plunger 11 is hollow through the major portion of its length and its upper end is provided with a flange 21. Adjacent the flange 21, the walls of the plunger are tapered as at 22 to limit the distance to which the plunger 11 can be inserted into the body 10 and also to form a fluid and airtight seal with the upper end of the body 10. The lower end of the plunger, in the embodiment shown in Figures 1 through 3, is provided with a central bore 23 to receive the post 24 of a sealing member 25. The sealing member 25 is generally cylindrical in form but is provided with an annular groove 26 V-shaped in cross sec-

tion as shown to perform the functions of the conventional cup leathers.

The vial 12 is preferably provided with a flange 27. The flange 27 is provided with an enlarged bore 28 forming a shoulder adapted to receive the flange 29 of the plug 13.

The flange 29 is provided with a bore 30 adapted to receive the reduced portion 19 of the body 10. Initially the parts will be as shown in Figure 1 but as the parts are driven home, Figures 2 and 3, the enlarged portion 19a enters the bore 30, expanding the somewhat resilient vial 12 and making a secure seal therewith. The flange 29 is also provided with one or more bores 20a, corresponding in number to the number of pins 20 and so spaced as, in one position, to receive the pins 20 and permit further insertion of the portion 19 within the bore 30.

The vial 12 is generally cylindrical in shape but is provided, at its lower end, with a reduced extension 34. The plug 13 is conical in shape to provide ample clearance with the inner walls of the vial 12 for storage of fluid and has a lower end closure 34.

The plug 13 is initially provided with a V-shaped groove 32 to permit the escape of air when the plug is inserted in the vial. The plug and vial are then heat-sealed to close this opening.

The body 10, plunger 11, vial 12 and plug 13 are all preferably formed of polyethelene plastic and the plug 13 is so dimensioned with respect to the interior of the vial 12 and the enlarged bore 28 as to have a press fit therewith, thus assuring that when the device is in the position shown in Figure 1, the vial is surely and securely sealed against contamination and infection. In fact, since the vial 12 is formed of plastic and has a certain amount of elasticity the outer diameter of the plug is preferably a small amount larger than the inner diameter of the vial, the vial expanding when the plug is driven in, thus assuring that the vial will remain sealed while the device is being handled and manipulated.

The device, as shown in Figure 1, is in the condition in which it is intended it will be supplied by the manufacturer to the user or distributor.

Any suitable injectable fluid 33 is retained within the vial 12 and the walls of the vial 12 are so proportioned with respect to the walls of the plug 13 as to retain the desired amount of fluid between them. When it is intended to make use of the syringe, the user will rotate the body 10 with respect to the vial and plug until the pin or pins 20 are aligned with the hole or holes 29a. Thus the pins 20 and the holes 29a constitute correlative members adapted to prevent movement into wall piercing position until said members are properly aligned. In this condition, the body 10 may be driven downwardly into the hollow plug 13, the reduced portion 19 thereof having a snug sliding fit with the interior of the plug. As this is done, the lower end of the needle 16 penetrates the bottom wall 34 of the hollow plug, as shown in Figure 4. This is accomplished because the elongated cavity in the plug 13 is provided with a length substantially equal to but slightly less than the combined length of the hub 19 and the free part of the needle 16. However, the devices are so dimensioned and proportioned that the needle does not pass sufficiently through the lower wall 34 of the plug to permit all of the opening 35 in the needle to pass therethrough. It has been discovered that in driving the needle through the plastic wall 34 the needle will pick up a portion of the plastic substance which will form a plug in

the end of the needle if the needle is permitted to pass sufficiently through the wall 34 to uncover all of the opening 35 and it has likewise been discovered that limiting the amount of movement, as above shown, insures that any plug which might be formed will be removed upon withdrawing the needle.

With the needle thus driven through the lower wall 34, the device is in the condition shown in Figure 4. With the device thus arranged, the operator may withdraw the plunger 11, as shown in Figure 3, thus causing the fluid 33 to pass upwardly through the needle and into the body 10, as shown in Figure 3. When this is done, the operator will then remove the vial 12 and plug 13 from the reduced portion 19 of the body and the syringe is in condition to be manipulated for the removal of any air bubbles. To do this the operator inverts the syringe so that the needle points upwardly and due to the tapered bottom 15 any air which is entrapped will be positioned at the opening of the needle into the body of the syringe; thus a small amount of movement of the plunger into the body will remove the air. It will also be apparent that this type of syringe can be aspirated by the user in order to make certain that the injection is not being made directly into a vein or artery.

When the device is used as a package for powdered medicaments of the type which must be mixed with a diluent shortly before injection the operator uses the same procedure with the exception that prior to removing the vial 12 and plug 13 from the body the plunger 11 is slowly reciprocated in the body 10 a number of times. Powdered medicament, preferably contained in the hollow end 38 of the member 25 is thus thoroughly dissolved in the diluent, or suspended therein, while the plug and vial remain sealed to prevent the escape of fluid.

Furthermore such repeated reciprocations of the plunger 11 in the body 10 tend to pick up and entrap small amounts of air which is held in the vial 12 under pressure and helps to force the fluid 33 into the body 10.

Referring now more particularly to Figure 5 there is shown an alternative embodiment in which the sealing member 25a, instead of being provided with a post 24 adapted to be driven into a bore 23 in the plunger, is provided with a hollow extension 36 which receives within itself a post 37 formed upon the plunger. In either case, the plunger 11 is hollow throughout the major portion of its length.

As previously stated, the plug 13 is so dimensioned as to have a driving fit with the enlarged portion 28 of the vial. The reduced portion 19 is so dimensioned as to have a close fit with the interior of the plug 13 and the plunger 11, and at its upper end is provided with a tapered wall 22 which, when the plunger is driven home, securely seals the upper end of the body. Thus, three fluid tight seals are provided in this assembly.

While a particular shape and size of vial has been shown, it will be appreciated that the vial will be so formed as to contain within itself the desired amount or dose of each separate injection and the extension 31 is positioned so that the needle 10, when driven home, will be positioned substantially at the bottom of vial 12 and thus will be capable of picking up into the body 10 substantially all of the injectable fluid contained within the vial.

The sealing member 25 is preferably made

with an outer diameter in the order of twenty thousandths (20,000ths) larger than the interior diameter of the body member 10 in order to insure that the sealing member will remain pressure tight within the body. This feature plus the general assembly of the device enables the operator to work the plunger 11 back and forth within the body 10 as many times as desired after the needle 16 has pierced the wall 34 for mixing and agitation of the fluid.

While there has been described what is at present considered a preferred embodiment of the present invention, it will be appreciated by those skilled in the art that various changes and modifications can be made therein without departing from the essence of the invention and it is intended to cover herein all such changes and modifications as come within the true spirit and scope of the appended claims.

I claim:

1. A syringe comprising: a hollow body member provided with a hub; a plunger normally received within said body member; a hollow needle extending from the end of said body member and said hub and communicating with the interior of said body member; a vial; and a hollow plug for closing said vial; said plug being normally disposed upon said hub and surrounding said needle having walls forming an elongated cavity having a length substantially equal to but slightly less than the combined length of the free portion of said needle and of said hub; said body member having a portion normally

20

5

received in said elongated opening in said hollow plug; said vial being disposed upon the plug at the opposite end of said body from said plunger; said body member in one position being adapted to be depressed further into said hollow plug to cause said needle to pierce a wall of said plug and communicate with the interior of said vial.

2. A device as set forth in claim 1 in which said needle in wall piercing position extends through the pierced wall sufficiently to permit withdrawal of fluid from said vial into said body but insufficiently to permit the opening in said needle to pass completely through said wall.

3. A device as set forth in claim 2 in which said hollow body and said plug are provided with correlative members adapted to prevent movement into wall piercing position until said members are properly aligned.

ROBERT W. OGLE.
